UNITED STATES PATENT OFFICE.

CHARLES G. SMITH, OF DETROIT, MICHIGAN.

EXCELSIOR-MACHINE.

SPECIFICATION forming part of Letters Patent No. 410,564, dated September 3, 1889.

Application filed January 17, 1889. Serial No. 296,684. (No model.)

To all whom it may concern:

Be it known that I, CHARLES G. SMITH, a citizen of the United States, residing at Detroit, in the county of Wayne and State of Michigan, have invented a new and useful Excelsior-Machine, of which the following is a specification.

My invention relates to improvements in that class of excelsior-machines in which the knife runs in a frame; and it consists in placing the knife in a frame operating in conjunction with the carriage or feed for propelling the block, and the lever and bars for regulating the speed of the carriage or feed.

The objects of my improvements are, first, to increase the production of excelsior; second, to save labor, and, third, to reduce the cost of this commodity. I attain these objects by the mechanism illustrated in the accompanying drawings, in which—

Figure 1 is a sectional view of the entire machine as it appears after the block is inserted in frame of carriage. Fig. 2 is a rear view of the carriage or block frame. Fig. 3 is a rear view of the machine. Fig. 4 is a front view of the carriage or frame. Fig. 5 is a view showing the knives in a position to cut. Fig. 6 is a front view of the large knives. Fig. 7 is a sectional view of the knives. Fig. 8 is a top view of the knife-case. Fig. 9 is a top view of the small knife or slitter. Fig. 10 is a side view of the small knife or slitter. Fig. 11 is a front view of the large shaving-knife. Fig. 12 is a back view of the large shaving-knife. Fig. 13 is a view showing the knives, large and small, sliding into position in the frame. Fig. 14 is a back view of the case, looking from the rear of the machine, showing the knives, drive-wheel, pitman, and brace. Fig. 15 is a view of the upright bar. Fig. 16 is a view of the weight which actuates the block-carriage.

Similar letters refer to similar parts throughout the several views.

X is a sectional knife composed of A, B, C, C', and G. The shaving-knives A (see Figs. 11 and 12) and the slitting-knives B (see Figs. 9 and 10) are made in any number of sizes, and numbered 1, 2, 3, &c., the only difference in the sizes of the knives being that No. 2 is the one-hundredth part of an inch, more or less, thicker than No. 1, according to the thickness of the

shaving desired, thus causing the edge *t* of shaving-knife A and the point *N* of slitting-knives B to project out over No. 1 sufficiently 55 to make the thickness of shaving desired, knife No. 3 being the same degree thicker than No. 2, and so on up to the highest number. (See Fig. 7.) A and B are slid into the groove in frame C on top of plate C'. (See 60 Fig. 13.) The knives A and B may be inserted alternately, as shown in Figs. 5, 6, and 7, or one slitting-knife B may be used for one or more of the shaving-knives A. After the desired number of knives A and B are inserted in frame C, plate or cross-head G is set 65 on top and secured by means of bolts or screws, which hold the knives firmly in position; or a thumb-screw K, passing through plate G, the lower end of screw resting upon 70 top of upper knife, may or may not be used, as it forms no part of my invention and is not necessary to the proper working of the other parts, the shaving-knives being formed with groove or opening *a* to allow the shavings to pass through. This combination of 75 plate C', frame C, the shaving and slitting knives, and the top plate G constitutes my excelsior-knife X, which in this machine reciprocates in an iron frame set in standard D, 80 but is designed to run in either a vertical or horizontal position. The slitting-knives B pass over the block first and slit the surface of the block into narrow strips any desired width, and knives A, following, shave off 85 shavings the desired thickness. These thin narrow strips pass out through groove or opening *a* as excelsior, ready for packing into bales.

Knife X is actuated by the pitman F, one end of which is attached to cross-bar L and 90 the other end to the wheel E, which is actuated by pulley *i* on shaft *x*, belt *f* supplying the power. Any other suitable gearing may be substituted for E, *x*, *i*, *f*, and L, this shown being of the simplest construction and forming no part of my invention.

The block carriage or feed is formed by cog-bar U and frame N, cast or framed together, U resting upon bottom of groove in table supplied with roller *r* and propelled by 100 *h*, attached to pulley or wheel and bar *j* by cord or chain *i* to cog-wheel T, set above cog-bar U, and in addition to propelling carriage weight *h* holds the bar U firmly in place,

giving it a smooth steady motion. Crank *l* is used to run the carriage back into position to receive fresh block *Q*. *r*, *U*, and *T* are fitted into and run in a groove running lengthwise 5 of the table, (see Fig. 3,) which groove runs the whole length of the table.

g is an iron plate slightly raised above the surface *s* of the table *b*, upon which the block *Q* rests while the knives are descending.

10 *k* is an iron plate fastened to the standard above the block, which helps to hold block firmly in position while the knives pass upward.

Bar *R* is attached to standard *N* by means 15 of a hinge and rests upon point *m* in slot in brace *S*. The teeth or cogs are so set that it passes forward on being slightly raised, but sets firmly when pressed backward and helps to hold the block firmly in position.

20 *P* is the plate or frame forming the upper part of block-frame and attached to the carriage by a hinge, and, like the bottom of the block-frame, is supplied with spurs *v*, together forming a clamp which holds the block firmly 25 in the frame.

O is the lever to plate *P*.

The speed of the carriage is regulated by bar *Y* and lever *W*. *W* is attached to center brace *S* by a hinge. To the lever *W* is attached bar *Y*, which has slots *e*, (see Fig. 15,) 30 with shoulders to hold flange on bar *R*, which passes through it. The point of bar *Y* rests in the teeth of bar *U*. When knives move upward, the point of lever *W* is caught by top of knife *C* and carried up to dotted lines. 35 This raises the point of bar *Y* out of teeth of bar *U*, and raises bar *R* above the point *m*. The weight *h* then forces the carriage forward until the block *Q* rests against the plate *C* in 40 position for knives *B* and *A*. As soon as the knives begin to descend, lever *W* drops to the bottom of slot *Z*. This allows bar *R* and the point of bar *Y* to fall into position, holding the block back until the knives have 45 passed upward into position. Catch *y* is fastened to the table *b* by hinge *d*, and holds

carriage in position when run back by crank *l* and while slab is being removed and fresh block *Q* inserted, as shown in Fig. 1.

I am aware that excelsior-machines have 50 been made running a single shaving-knife and slitting-knife in a vertical or horizontal position. I therefore do not claim such a combination broadly; but

What I do claim as my invention, and desire 55 to secure by Letters Patent, is—

1. The combination, in an excelsior-machine, of the frame *C*, to receive the plate *C'*, the shaving-knives *A*, and the slitting-knives *B*, the plate *C'*, fitted in the frame *C* at the 60 bottom to support the knives, the shaving-knives *A*, fitted in the frame *C* and resting on top of the plate *C'*, the slitting-knives *B*, fitted in the frame *C*, resting on top of one or more of the shaving-knives *A*, the plate or 65 cross-head *G*, set on and fastened at top of the frame *C* to retain the knives in place, all substantially as set forth.

2. In an excelsior-machine, the combination of the frame *C* and the plate *C'*, to receive the shaving-knives *A* and the slitting-knives *B*, the shaving-knives *A*, the slitting-knives *B*, the top plate or cross-head *G*, to retain the knives in the frame *C*, the standard *D*, in which the frame *C* reciprocates, and 75 the table *b*, which supports the block to be cut up, all substantially as set forth.

3. The combination, in an excelsior-machine, of a table or bench *b*, provided with groove, the groove running full length of table, in which the cog-bar *U*, supporting the carriage-frame *N*, runs, the cog-bar *U*, supporting carriage, the carriage-frame *N*, to carry the block, propelled and held in position by the cog-wheel *T*, the cog-wheel *T*, the 80 bar *i*, and the weight *h*, which forces the block toward the knives, substantially as 85 shown and set forth.

CHARLES G. SMITH.
